UNITED STATES PATENT OFFICE.

WILLIAM SPARTIVENTO, OF BUFFALO, NEW YORK.

HACK SAW.

Application filed July 12, 1924. Serial No. 725,561.

To all whom it may concern:

Be it known that I, WILLIAM SPARTIVENTO, a citizen of the United States, residing at Buffalo, in the county of Erie and 5 State of New York, have invented certain new and useful Improvements in Hack Saws; and I do hereby declare the following to be a full, clear, and exact description of the invention, such as will enable others 10 skilled in the art to which it appertains to make and use the same.

This invention relates to a hack saw.

It is primarily aimed to provide a construction wherein the manipulating elements 15 of one or more of the blade securing means or devices may remain in a position in line with the frame regardless of the angle at which the blade is disposed, to secure compactness and prevent interference of such 20 element or elements with adjacent work or the like.

The present invention is in the nature of an improvement over that disclosed in my pending application 649,305, filed July 3rd, 25 1923, for Letters Patent for a hack saw, allowed March 31st, 1924.

The more particular objects and advantages will become apparent from a consideration of the description following taken 30 in connection with the accompanying drawings illustrating an operative embodiment.

In said drawings:—

Figure 1 is a side elevation of a hack saw constructed in accordance with the invention;

Figure 2 is a sectional view taken on the line 2—2 of Figure 1;

Figure 3 is a sectional view taken on the line 3—3 of Figure 1;

Figure 4 is a sectional view taken on the line 4—4 of Figure 1;

Figure 5 is a sectional view taken on the line 5—5 of Figure 1;

Figure 6 is a plan view of the lever operable stem but with the sections thereof detached, and

Figure 7 is a perspective view of the lever engaging washer.

Like reference characters designate like 50 or similar parts in the different views.

In carrying out the invention, a generally U-shaped frame or beam is provided at 10, preferably being in extensible sections to accommodate various length of saw blades

55 11. A handle 12 extends from frame 10 and the terminals of said frame have fittings or

barrels 13 and 14. The barrel 13 at its inner end has one or more notches or recesses as at 40 and slidably in the barrel 13 is a stem 41 consisting of sections 42 and 43. Section 43 60 has a socket of key hole shape as at 44 which detachably receives a correspondingly shaped coupling projection 45 which constitutes a swivel permitting free turning or rotation of the section 42 within the barrel 13 and 65 relatively to and independently of the section 43. Section 43 is normally held against rotation within the barrel by means of a pin or key 46 carried thereby adapted to engage the notches 40. Section 43 may slide longitudinally of the barrel so that the key 46 may be engaged in selected notches 40, according to the angularity desired for the blade 11. Blade 11 has an aperture at the adjacent end adapted to receive a stud 47 of 75 section 43 and be exteriorly overlapped by a slideable latch 48 pressed outwardly by an expansive spring 49, located in a recess 50 of said sections 43. This latch in its projected position abuts the stud 47 as well seen in 80 Figure 2 so that the blade cannot become accidentally detached. Incidental to attachment or detachment of the blade the latch 48 is manually moved to retracted position against the tension of the spring 49. The 85 outer end of section 42 is bifurcated and a cam lever 51 is operable in the bifurcation being pivoted at 52 to said section 42. A washer 53 engages the outer end of the barrel 13 and is slotted at 54 so that it may 90 slip over the bifurcated portions of section 42 and such section may slide relatively to the washer and the washer turn with the section. It will be seen that when the lever 51 is in a released position, the stem as a 95 whole is free for sliding movement so as to engage the key 46 in any of the notches 40 according to the angularity desired for the saw 11. Before the lever 51 is moved to its fastened position it may be turned 100 from the axis of the stem, as is permissible by the ball and socket joints at 44 and 45, to place the stem in the desired relation to the frame 10.

The stem 16 and adjacent parts may be of 105 the same construction and operable axially and rotatably in the same manner as the corresponding parts in my said pending application 649,305.

The present construction, like that of my 110 pending application aforesaid, particularly permits the blade to be adjusted to various

angles and to be fastened in the different positions due to the engagement of the collars 19 and 53 with the barrels. In the present form, however, regardless of the angularity of the saw blade 11 and the adjustment of the stems, the lever 51 may remain at its manipulating end in line with the saw, that is between the planes of the opposite sides thereof, thus avoiding disposition at 10 an angle to the frame as in the form of said pending application, and which in instances causes interference with the work in hand and with adjacent structure.

What is claimed is:

- 15 1. In combination, a frame provided with a barrel, a stem section journaled and slideable in the barrel, securing means for a tool carried by said section, a second tool stem section slideable and journaled in said barrel, 20 means connecting said sections together to permit turning of one of them with respect to the other and about their longitudinal axis, interengaging fastening means between one of said sections and said barrel, and a 25 lever to coact with the barrel to fasten the parts in operative position.
2. In combination, a frame provided with a barrel, a stem section journaled and slideable in the barrel, securing means for a tool 30 carried by said section, a second tool stem section slideable and journaled in said barrel, a swivel connection between said sections, coacting fastening means between one of said sections and said barrel, the other section be-

ing bifurcated, a washer threaded on the 35 last mentioned section adjacent the bifurcation, and a lever in the bifurcation adapted to abut the washer and cause the latter to abut the barrel.

3. In combination, a frame provided with 40 a barrel, said barrel at its inner end having notches, a stem section journaled and slideable in the barrel having a key selectively engageable with said notches, securing means for a tool carried by said section, a second 45 tool stem section being slideable and journaled in said barrel and having swivel connection with the first mentioned section, and a lever to coact with the barrel to fasten the parts operatively.

4. In combination, a frame provided with a barrel, said barrel at its inner end having notches, a stem section journaled and slideable in the barrel having a key selectively engageable with said notches, securing means 55 for a tool carried by said section, a second tool stem section being slideable and journaled in said barrel and having swivel connection with the first mentioned section, a lever to coact with the barrel to fasten the 60 parts operatively, the second mentioned stem section being bifurcated and receiving the lever in the bifurcation, and a washer threaded on the bifurcated parts to abut the barrel and be abutted by the lever.

In testimony whereof I affix my signature.

WILLIAM SPARTIVENTO.
